Edward S. Beach
ATTORNEY

UNITED STATES PATENT OFFICE.

JOHN PETER WEIS, OF NYACK, NEW YORK, ASSIGNOR OF ONE-HALF TO METROPOLITAN SEWING MACHINE CORPORATION, OF DOVER, DELAWARE, A CORPORATION OF DELAWARE.

THREAD-BREAKING MECHANISM.

Original application filed October 16, 1914, Serial No. 867,005. Renewed December 24, 1919, Serial No. 347,189. Patent No. 1,348,526, dated August 3, 1920. Divided and this application filed January 2, 1919. Serial No. 269,277.

To all whom it may concern:

Be it known that I, JOHN PETER WEIS, a citizen of the United States, residing at Nyack, in the county of Rockland and State of New York, have invented certain new and useful Improvements in Thread-Breaking Mechanisms, of which the following is a specification.

This invention relates to thread-breaking mechanism for sewing machines especially, and is especially useful in bodily-moving sewing-machine heads. This application is a division of my application Serial No. 867,005, filed October 16, 1914, renewed December 24, 1919, Serial No. 347,189, and patented August 3, 1920, No. 1,348,526, and shows the weighted crank and pitman needle-drive together with the automatically adjusting work-holding foot mechanisms shown in my application Serial No. 269,273, filed January 2, 1919, on which Patent No. 1,419,087 was granted June 6, 1922, and which latter application is also a division of said application Serial No. 867,005 on which said 25 Patent No. 1,348,526 was issued.

In the accompanying drawings forming a part hereof,

Fig. 1 is a perspective view of the front end of a sewing-machine head embodying this invention.

Fig. 2 is an end view of the throat-plate work-holding foot, looper and looper thread pull-off slide and thread-breaking mechanisms assembled, the needle being also shown.

Fig. 3 is a top plan view of the throat plate and shows the looper thread pull off slide in two positions, the full line position indicating its operative and the dotted line position indicating its inoperative position.

Fig. 4 is a perspective view of the looper thread pull off slide.

Fig. 5 is an end elevation of what is shown in Fig. 3 looking in the direction of the arrow.

Figs. 6 and 7 are partial sectional views of the throat-plate, looper thread pull off slide and looper thread finishing plate carried by the throat-plate, both figures at section line 6-6 of Fig. 5 looking in the direction of the arrow shown in Fig. 5, and illustrate the looper in different positions operating on the looper thread. Fig. 6 shows

the thread pull off slide in its operative position during the stitching and Fig. 7 shows the tread pull off slide in thread pull off position after the stitching operation is completed.

Fig. 8 is an enlarged view of what is shown in Fig. 6 but with goods in place and the needle and looper threads in working relation to the goods and to one another, the needle being down through the goods and the looper in a backward position.

Fig. 9 is an enlarged view of what is shown in Fig. 7 but with goods in place, the needle and looper threads in working relation one to another and the needle being above the goods and the looper in its most forward position.

Herein the yielding work-holding foot is indicated by F, the needle by N, the looper by L, the looper shaft by M, the upper sewing-machine arm by A, and the under arm by A'.

The throat plate P carries a lever 1 for actuating a bottom or looper thread pull off slide, the lever being pivoted at 2 to an arm 3 of the throat plate which has in its upper surface a slideway 9^a for the pull off slide 5 which at 4 is pivoted to an end of lever 1. The front end 6 of the pull off slide has in its forward end portion a needle hole 7 that is elongated rearwardly at 7^a. The needle hole 8 through the throat plate is formed in the bottom wall of the slideway which is partially covered lengthwise by a looper thread pinch plate 10 that is fixed at 11 to the upper wall of the throat plate. As shown in Fig. 4, half the thickness of the pinch plate 10 is cut away lengthwise of it at one under margin 12 that overhangs the bottom thread pull off slide. The width of the reduced marginal portion 12 is the same as that of the pull off slide. Between its ends, this pinch plate on its underside, is formed with a transverse under or looper thread clamping or pinching lip shoulder or vertical wall 13

so as to form a transverse lip 14 of about the width of the pull off slide; and forward of this lip 14 the front end portion 16 of the pinch plate forms a bottom thread breaker plate which is of the thickness of the marginal portion 12. As viewed in Fig. 4, the pinch plate 10 is stepped on its under-surface; and it is secured by the fas-

teners 11 to the upper surface of the throat plate with the free end of its breaker plate 16 extending forwardly but terminating rearwardly of the needle hole 8 through the 5 throat plate (Figs. 6 and 7). For the reason that, in the assemblage, the breaker plate 16 overhangs the pull off slide and is spaced above it, a vertical guard shown in the form of a pin 17 is located at the front 10 end of the breaker plate at one side of the slideway for the purpose of preventing threads or goods from getting in under or hooking on the front end of the breaker plate the executive or work performing end 15 of which is crosswise of the pull off slide.

As shown, the throat plate is provided with a band saw guard 18.

The mode of operation during stitching is as follows:

20 The looper thread indicated by *a* leads from a source of supply through the back and front eyes of the looper blade in the usual manner, and leads through the front looper eye upwardly through the needle hole 25 8 of the throat plate and extends thence through the needle hole 7 of the pull off slide; and thence to the last stitch in the goods. The needle thread *b* is carried by the needle downwardly through the needle 30 hole 7 when it is over the needle hole 8 and the needle thread loop is entered by the thread-carrying looper blade as the needle rises; at which time the needle thread loop *b* is drawn up against the underside of the 35 looper blade. When the needle in its upward movement has been stopped at the end of any stitching operation, the bottom thread pull off slide is retracted; the front wall of its needle hole 7 then pulls slack 40 bottom thread rearwardly and against the back wall of the needle hole 8, the upper end of the bottom thread being anchored in the goods which are fed rearwardly by feed rolls (not shown) simultaneously with the 45 retreat of the pull off slide. During such rearward movements of the goods and of the breaker slide, the bottom thread is by said rearward movements pulled over the front edge of the breaker plate 16, the bottom 50 thread then running through the needle holes 7 and 8 and the eyes of the looper blade. The pull of the feed rolls on the goods breaks the needle thread loop across the under edge of the looper blade, and simultaneously, at the completion of the backward 55 movement of the breaker slide, the bottom thread is broken across the breaker plate 16, the bottom thread being at this time pinched between the clamp lip 14 of the pinch plate 60 and the then opposed front marginal wall portion 9 of the needle hole 7. The inner edge of the throat plate is preferably bent down at 19 to prevent goods and thread from catching on the throat plate. This 65 action of the bent down inner margin of the

throat plate is especially important in bodily-movable sewing machines provided with cutting means of the type shown in my said Patent No. 1,348,526 of August 3, 1920 and in my prior Patent No. 1,114,082, 70 wherein the goods are fed flatwise from front tensioning devices by main feed rolls, and consequently if there is a hole in the goods and such hole is approaching the stitch-forming instrumentalities, the bent-down end is not liable to catch into the hole and arrest the forward progress of the goods. The throat plate is provided with a hole 20 rearwardly of its needle hole to give freedom of movement to the bottom thread 75 when it is in the position shown in Fig. 7.

It will be observed that the looper thread *a* has three bends in a vertical plane, one bend over the rearward edge of the needle hole in the throat plate, the next or intermediate bend over the forward edge of the breaker slide needle hole, and the third over the forward edge of the breaker plate. At the two end bends the looper thread is in frictional contact with the parts against 85 which they bear, and such friction causes sufficient restraint on the movement of the thread to permit the breaker slide to move forward without moving the looper thread at the two end bends. Otherwise the thread 90 movement would tend to snarl the thread or otherwise interfere with the proper starting of the stitching; and also to move forward with the walls of the elongation of its needle hole slot 7 loosely straddling the looper 95 thread between the two end bends. If it were not for the elongation of the needle hole slot 7 the thread would be apt to be pinched by the pull off slide in its forward movement, and so interfere with the feeding 100 of the goods.

The under or looper thread-breaker slide 110 is also a looper thread measuring device because on its backward movement it pulls off the required length of under or looper thread for the commencement of the next sewing movements of the needle and the looper; and while the thread is pinched at 115 15 by the under or looper thread clamping or pinching lip 14 it is broken over the end 16 in consequence of the strain of the feed of the goods. In the pinching movement the plate 10 is slightly sprung up by the thread drawn between it and the breaker slide.

The clearances referred to are indicated by 12^a and 16^a, and they permit the looper thread to find its intermediate bend to loop around and be drawn under the thread-pinching lip 14.

Referring to the enlarged views of Figs. 8 and 9, Fig. 8 shows the needle down and the looper back and the breaker-slide forward. The needle thread *b* has one strand extending in the direction of the arrow to 130

- a thread supply not shown. The free end of the upper strand of the needle thread is adjacent the upper side of the goods, the first descent of the needle in stitching the goods G having occurred. The free end of the looper thread α is adjacent the under side of the goods and out of contact with the breaker-slide and extends up through the elongated opening 7^a of the breaker-slide.
- 10 When, at the end of a seaming operation, as indicated by Fig. 8, the needle stops in its upper position above the goods, the looper is forward through the needle thread loop and the free end of the needle thread strand instead of being up through the goods has been broken at the under side of the goods by the operation of the feed of the goods and appears adjacent the under side of the goods. After the needle has stopped in its up position the breaker-slide moves rearwards into the position shown in Fig. 9 and the looper thread is broken over to the edge of the pinch plate, as above described; the free end of the looper thread then being in the position shown in Fig. 9. After the end of the sewing operation, above referred to, any further feed of the goods will obviously pull the free end of the needle thread strand out of the position shown in Fig. 7 and such free end will be carried by the operation of the machine into a position above the goods where, at the beginning of a second sewing operation, the positions of the parts shown in Fig 8 will be repeated.
- 35 What I claim is,—
1. The combination in a sewing machine, of stitch-forming instrumentalities, a throat plate, and thread-breaker mechanism carried by the throat plate, said thread breaker mechanism comprising a slide formed with an elongated needle hole; a stationary thread breaker plate located in the path of the looper thread to be broken; and the
- throat plate having a needle hole with which the needle hole through the slide is registerable; and a thread carrying looper.
2. In the structure of claim 1, the thread-breaker mechanism comprising a throat plate having a thread clearance rearward of the needle hole; a plate fixed to the throat plate to keep the breaker slide in place, the plate having on its inward side a transverse under thread clamping lip cooperating with the front end of the breaker slide to clamp the thread.
3. In the structure of claim 1, the thread-breaker mechanism comprising a throat plate having a thread clearance rearward of the needle hole; a plate fixed to the throat plate to keep the breaker slide in place, the plate having on its inward side a transverse under thread clamping lip cooperating with the front end of the breaker slide to clamp the thread; and a guard for the mouth of the clearance.
4. The combination of a throat plate having a needle hole; a thread carrying looper; a stationary looper thread breaker; a pull off slide having an elongated needle eye; and a yielding looper thread pinch plate having a looper thread pinching lip.
5. The combination with a sewing mechanism comprising a needle; a looper; a presser-foot and a throat plate having a needle eye through it of a reciprocating slide mounted in a guide-way at the upper surface of the throat plate, the front end of the slide forming a looper thread breaker; a stationary pinch plate covering the slide in the guide-way and forming a looper thread pinching member, the slide having an elongated needle slot extending lengthwise of it.
- In testimony whereof I have hereunto set my hand this 27th day of December, 1918.

JOHN PETER WEIS.
